UNITED STATES PATENT OFFICE.

PETER HAMMER, OF COMPTON, CALIFORNIA, ASSIGNOR OF ONE-HALF TO THOMAS COLLINS, OF COMPTON, CALIFORNIA.

WRENCH.

Application filed October 6, 1924. Serial No. 741,906.

This invention has to do with a wrench and it is an object of the invention to provide an effective, improved, quick, adjustable wrench.

5 An object of this invention is to provide a quick adjustable wrench which is extremely simple and convenient to operate.

Another object of this invention is to provide a quick adjustable wrench which is positively set when the jaws are in operative position.

10 A further object of this invention is to provide a wrench of the character described which is simple, effective and practical in construction.

15 The objects and features of my present invention will be best and more fully understood from the following detailed description of a typical form and application of the invention, throughout which description reference is had to the accompanying drawings in which

20 Fig. 1 is a side elevation of a wrench embodying a typical form of the present invention.

25 Fig. 2 is a sectional view of the wrench shown in Fig. 1.

30 Fig. 3 is an enlarged transverse sectional view taken substantially as indicated by line 3—3 on Fig. 1 showing the wrench in released position, that is, in position to allow for adjustment for the jaws, and

35 Fig. 4 is a view similar to Fig. 3 showing the wrench set or in position for operation.

40 My present invention is, in its broader sense, applicable to wrenches of various types and is capable of embodiment in various forms of construction. I have, for purpose of illustration only, chosen to set forth the invention in a wrench of the type usually employed for handling pipe, and the like, and have set forth a simple and typical form of construction. It is to be distinctly understood that the disclosure made in this application is not to be considered as limiting the scope or range of application of my invention.

45 The tool illustrated in the drawings includes, generally, a handle 10, a relatively stationary jaw 11, an adjustable jaw 12 and various other parts, the details of which will be hereinafter set forth. The handle 10 is

designed so that its outer end portion 13 forms a handle for the tool, while its inner portion carries the working parts of the tool. 55 The handle 10 may, as far as the present invention is concerned, be designed and constructed in the manner usual to devices of this general character.

The jaw 11 is a stationary jaw connected or formed with the handle 10. In the particular case illustrated in the drawings, the jaw is rigidly mounted on the inner end of the handle 10. The jaw is formed separate from the handle and is secured thereto by a 60 suitable pin 14.

The jaw 12 is located immediately beyond or outward of the jaw 11 and is connected with the handle 10 so that it is adjustable toward and away from the jaw 11. In the 70 particular type of wrench illustrated in the drawings the jaw 12 is connected with the handle 10 by means of a shank 15 provided on the jaw 12 and a carrier 16 which is provided on the handle 10 and carries the shank 75 15. The shank 15 is preferably formed with the jaw 12 and is substantially parallel with the handle 10. The carrier 16 provided on, or in connection with, the handle 10 is in substance a part or continuation of the handle 10. In the particular construction shown in the drawings the carrier 16 is formed 80 separately from the handle and is connected thereto by a pivot pin 18. The carrier and handle are related so that the carrier has a 85 limited pivotal movement with reference to the lever. The carrier extends longitudinally of the lever and is located at the rear of the handle as clearly illustrated in Fig. 1 of the drawings. The pivotal connection 90 between the carrier and handle is at the inner end of the carrier. A spring 20 is arranged in connection with the other end of the carrier to normally yieldingly hold it away from the handle. Projections 21 on 95 the carrier cooperate with stops 22 on the handle to limit the amount the carrier is moved by the spring.

In the preferred form of my present invention the shank 15 of the jaw 12 is round 100 in cross-sectional configuration and is carried in a round opening 24 in the carrier 16. The shank is carried in the opening 24 so that it can be rotated and also moved lon-

gitudinally with reference to the carrier. In practice the carrier is made sufficiently long so that the shank has a fairly long bearing in the carrier.

My present invention provides means whereby operation of the shank longitudinally in the carrier is controlled by relative rotation between the shank and carrier. This means is such that the shank is positively set against longitudinal movement in the carrier when the jaw 12 is in alignment with the jaw 11 and is free to move longitudinally with reference to the carrier when the shank is rotated to a position where the jaw 12 is out of alignment with the jaw 11. This means includes a series of projections or teeth 30 formed in the shank 15 and a series of corresponding projections or teeth 31 projecting from the wall of the opening 24 in the carrier. The series of teeth 30 and 31 are located and related so that they mesh or are in cooperative engagement when the shank 15 is positioned so that the jaw 12 is in alignment with the jaw 11. A recess 35 is formed in the shank adjacent one side of the series of teeth 30 to receive the teeth 31 when the shank is rotated from the position just described to a position where the jaw 12 is out of alignment with the jaw 11. The recess 35 is made sufficiently large to freely carry the teeth 31 so that the shank is free to move longitudinally in the carrier when the parts are in the last mentioned position. In Fig. 3 of the drawings I illustrate the parts in position with the teeth 31 in the recess 35 so that the shank is released and free to move longitudinally while in Fig. 4 I illustrate the parts in position where the teeth 30 and 31 are in mesh so that the shank is positively held against longitudinal movement. In practice the series of teeth 31 may be formed directly on the wall of the opening 24 or they may be formed on a block 40 set in a suitable socket 41 provided in the wall of the opening. The block may be releasably held in the socket by screws 42 so that it can be readily removed and replaced. In practice the tool can be constructed with more than one set of cooperating teeth without departing from the spirit of the invention.

A locking device or means is preferably provided for the purpose of yieldingly holding the shank 15 against rotation from the position where the teeth are in mesh and in the position where the teeth are released. This device may be in various forms, for instance, it may be in the form of a plunger 40^a carried by the carrier to cooperate with suitable notches or indentations 41^a in the shank. The plunger 40^a is operated by a spring 42^a confined in an opening 43 in the carrier between the head 34 of the plunger in a plug 35^a in the outer end of the

opening. When the parts are in the set or operating position, that is, when the jaws are in alignment and the teeth are in mesh, the plunger extends into one of the notches and yieldingly prevents accidental rotation of the shank and thereby holds the tool in the set position. When the tool is released, that is, when the jaws are out of alignment and the teeth disengaged, the plunger extends into the other notch and thereby holds the parts in the released position.

In using the tool the operator rotates the shank 15 in the carrier 16 by gripping the handle 10 in one hand and the jaw 12 in the other hand and then twisting them relative to each other in proper direction. By twisting the jaw with reference to the handle the shank is rotated in the carrier. To set the wrench for work the operator rotates the jaw 12 out of alignment with the jaw 11, slides the shank 15 in the carrier until the jaw 12 is the desired distance from the jaw 11 and then rotates the jaw 12 back into alignment with the jaw 11. The adjustable jaw 12 is then set or fixed with reference to the jaw 11, ready for operation. The plunger and notch device operate to automatically yieldingly hold the parts in the set or released positions upon their being moved thereto. To change the adjustment of the tool the operator twists the jaw 12 relative to the handle to rotate the shank so that the teeth 30 move out of engagement with the teeth 31 whereupon the shank can be moved longitudinally and set in the manner just described.

Having described only a typical preferred form of my invention I do not wish to limit myself to the specific details hereinabove set forth, but wish to reserve to myself any changes or variations that may appear to those skilled in the art or fall within the scope of the following claims.

Having described my invention, I claim:

1. A wrench including, a handle, a carrier pivotally mounted on the handle and having an opening through it, a stationary jaw on the handle, an adjustable jaw, a shank carrying the adjustable jaw and freely carried in said opening, the wall of said opening being provided with projections, the shank being provided with a series of teeth to cooperate with the projections to prevent movement of the adjustable jaw, the shank having a recess adjacent the teeth to receive the projections when the teeth and projections are out of engagement, and means in the carrier for yieldingly holding the shank against rotation when the teeth and projections are in engagement.

2. A wrench including, a handle, a stationary jaw on the handle, a carrier pivotally mounted on the same handle and having an opening through it, a movable

jaw, a shank on the movable jaw freely carried in the opening, the wall of said opening being provided with projections, the shank being provided with a series of teeth to cooperate with the projections of the carrier, the shank having a recess adjacent the teeth to receive the teeth of the carrier, and a spring pressed plunger mounted in

the carrier to extend into the opening and operate to yieldingly hold the shank ¹⁰ against rotation.

In witness that I claim the foregoing I have hereunto subscribed my name this 19th day of Sept., 1924.

PETER HAMMER.
